UNITED STATES PATENT OFFICE.

DAVID F. FORWOOD, OF TAYLOR, TEXAS.

DESIGN FOR A GRAVE LINING.

Application filed June 3, 1924. Serial No. 9,786. Term of patent 7 years.

To all whom it may concern:

Be it known that I, DAVID F. FORWOOD, a citizen of the United States, residing at Taylor, in the county of Williamson and State of Texas, have invented a new, original, and ornamental Design for Grave Lining, as shown in the accompanying drawing and described in the following specification.

The single figure of the drawing illustrates the new design for grave lining.

I claim:

The ornamental design for a grave lining as shown.

DAVID F. FORWOOD.
